METAL SHEET

Onni S. Koskinen, Birmingham, Mich.

Application June 16, 1958, Serial No. 51,370

Term of patent 14 years

(Cl. D54—2)

Fig. 1 is a front elevation of a metal sheet showing my new design;

Fig. 2 is a sectional elevational view of the metal sheet in Fig. 1, the view being taken along the line 2—2 of Fig. 1;

Fig. 3 is another sectional elevational view of the metal sheet shown in Fig. 1, the view being taken along the line 3—3 of Fig. 1; and

Fig. 4 is still another sectional elevational view of the metal sheet shown in Fig. 1, the view being taken along the line 4—4 of Fig. 1.

I claim:

The ornamental design for a metal sheet, substantially as shown.
